(57) **CLAIM**

The ornamental design for a battery holding storage rack, as shown and described.

DESCRIPTION

FIG. 1 is a top left isometric view of a battery holding storage rack showing my new design, in accordance with a first embodiment;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof;

FIG. 7 is a right side elevation view thereof; and

FIG. 8 is a top left isometric view of the battery holding storage rack of FIG. 1, showing environmental structure in the form of a power tool battery stored in position on the battery holding storage rack, this view illustrating how the battery holding storage rack appears in use;

FIG. 9 is a top left isometric view of a battery holding storage rack showing my new design, in accordance with a second embodiment that is related to the first embodiment previously shown (but including variation in rack width);

FIG. 10 is a top plan view thereof;

FIG. 11 is a bottom plan view thereof;

FIG. 12 is a front elevation view thereof;

FIG. 13 is a rear elevation view thereof;

FIG. 14 is a left side elevation view thereof; and,

FIG. 15 is a right side elevation view thereof.

The broken dash lines in the figures depict portions of the battery holding storage rack that form no part of the claimed design. Neither the portions of the battery holding storage rack shown in broken dash lines nor the broken dash lines themselves form any part of the claimed invention.

The broken dash-dot-dot lines in FIG. 8 depicts environmental structure that forms no part of the claimed design. Neither the environmental structure shown in broken dash-dot-dot lines nor the broken dash-dot-dot lines themselves form any part of the claimed invention.

The battery holding storage rack of FIGS. 9-15 is shown with a symbolic break in its length using broken dash-dot lines. Neither the portions of the battery holding storage rack shown in broken dash-dot lines nor the broken dash-dot lines themselves form any part of the claimed invention. The appearance of any portion of the article between the break lines forms no part of the claimed design.
